ATTORNEY

John W. Hodson
WITNESS:

Patented Aug. 10, 1926.

UNITED STATES PATENT OFFICE.

IKE LEVINE, OF NEWARK, NEW JERSEY.

TELEPHONE ATTACHMENT.

Application filed September 3, 1925. Serial No. 54,324.

This invention relates to improvements in telephone attachments and more particularly to a unit for casting a beam of light upon the dial of an automatic telephone to illuminate the same when the telephone is to be used at night, or when installed in a poorly lighted part of a room.

Another object of the invention is to provide a lamp and attaching means therefor, which may be easily applied to, or removed from a telephone and which attaching means supports a battery for supplying current to the lamp and which is conveniently controlled by a switch provided on the battery casing.

A further object of the invention is to provide an attachment of the type mentioned which is simple in construction, cheap of manufacture and strong and durable for the purpose intended.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a front elevation of an automatic telephone with my invention applied thereto.

Figure 2 is a perspective view of my attachment per se.

Figure 3 is a vertical sectional view on the line 3—3 of Figure 2.

Referring more particularly to the drawing, the reference numeral 9 designates my telephone attachment in its entirety, and 10 an automatic telephone which includes a base 11 upon which is mounted the phone dial 12 operable for securing the telephone number desired. Rising from the base 11 is a post or standard 13 and it is from this post that my attachment 9 is supported.

45 My attachment 9 includes a bracket 14 formed from a single piece of spring metal, bent upon itself midway between its ends to provide an eye 15 and yieldable clamping jaws 16, the free ends of the material being 50 curved outwardly for permitting the jaw to be easily engaged with the post 13 of the telephone. A casing 17 is supported by the clamping ring or eye 15 and which houses a battery 18 for supplying current to an electric lamp which will be hereinafter fully 55 described.

The casing 17 is closed at one end by a swinging cover 19, while the lower end of the casing is provided with a threaded socket 20. A switch 21 is mounted exteriorly of the casing and is of a construction similar to the type of switches used in connection with pocket flash lights, while the battery 18 is of a type also used in flash lights. If desired a set screw 22 may be threadedly 60 mounted in the walls of the eye 15 for securely holding the casing therein, but it will be understood that the normal tendency of the eye is to compress about the casing, which is sufficient to support the casing and 65 battery.

Depending from one of the clamping jaws 16 is an arm 23 which supports a lamp socket 24 for receiving an electric lamp 25, protected by a suitable shade 26 for directing 70 the rays of light in a downward direction. The arm 23 is curved so as to throw the light from the lamp directly upon the dial 12 when the switch 21 is "on". If desired, the lamp may be adjustably supported from 75 the bracket 14, but in view of the fact that telephones are of a standard make, it is believed that the lamp may be stationarily supported by the bracket and disposed in such relation thereto to reflect a beam of 80 light directly upon the dial.

The arm 23 is of tubular construction to permit an electric wire 27 to pass therethrough for connection with the socket 24 and the free end of the wire 27 carries a fixture plug 28 for threading engagement with the socket 20 in the lower end of the battery casing and which electrically connects the battery with the lamp.

From the foregoing description, it will be 90 seen that my attachment will provide a convenience for persons using telephones of the dial type, as it often occurs that a telephone is installed in a corner of the room where the light is poor, or at night the telephone 100 may be used without illuminating the entire room. When the battery 18 becomes "dead" the same may be readily removed by lifting the cover 19 and withdrawing the same and substituting a fresh battery therefor.

105 What is claimed as new is:—

1. An attachment for telephones of the dial type comprising an attaching bracket having spaced yieldable jaws and an eye, a battery casing having a socket in one end thereof, a set screw for removably supporting said battery casing within said eye, an 110

electric lamp supported by a tubular arm depending from said bracket for reflecting a beam of light upon the dial of the telephone, a battery with said casing and electrically connected with said electric lamp by an electric cord passing through said tubular arm and having an attachment plug at its free end for reception in said socket for supplying current to said lamp, and a switch on said casing for controlling the flow of current to said electric lamp.

2. An attachment for telephones comprising-

ing a bracket formed of a single piece of springy material and bent to provide a compressible eye for removably supporting a tubular casing, the free ends of said material being spaced to provide clamping jaws for engagement with a support, a tubular arm depending from one of said jaws through which an electric cord is adapted to pass, and an electric lamp supported by said arm.

In testimony whereof I have affixed my signature.

IKE LEVINE.
